UNITED STATES PATENT OFFICE.

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 25, 1928. Serial No. 641,887.

My invention relates to railway traffic controlling apparatus, and particularly to apparatus of the type wherein governing apparatus carried on a train is controlled by energy supplied from the trackway.

I will describe several forms and arrangements of railway traffic controlling apparatus embodying my invention, and will then point out the novel features thereof in 10 claims.

In the accompanying drawing, Fig. 1 is a diagrammatic view showing one form of trackway apparatus embodying my invention. Fig. 2 is a view showing a modification 15 of the arrangement shown in Fig. 1 and also embodying my invention. Fig. 3 is a view showing another modification of the trackway apparatus shown in Fig. 1 and also embodying my invention. Fig. 4 is a view 20 showing another modification of the arrangement shown in Fig. 1 and also embodying my invention. Fig. 5 is a view showing still another arrangement of trackway apparatus embodying my invention. Fig. 6 is a view, partly diagrammatic, showing 25 one form of train carried apparatus adapted for co-action with the trackway apparatus illustrated in Figs. 1 to 5 and also embodying my invention. Fig. 7 is a view 30 showing a modification of the apparatus shown in Fig. 6 and also embodying my invention. Fig. 8 is a view showing another modification of the apparatus shown in Fig. 6 and also embodying my invention.

Similar reference characters refer to similar parts in each of the several views.

Referring first to Fig. 1, the reference characters 2 and 2^a designate the rails of a railway track over which traffic normally travels in the direction indicated by the arrow. These rails are divided by insulated joints 1 into a plurality of track sections A—B, B—C, etc.

Each track section is provided with a 45 source of track circuit current which, as here shown, is a secondary winding 4 on a track transformer designated by the reference character T with an exponent corresponding to the location, this secondary being connected across the rails at the exit end of the section. An impedance 5 is interposed between this secondary and one rail of the section whereby the current output of the transformer is limited to a safe value when

its terminals are short-circuited by the wheels and axles of a train occupying the corresponding section. Each track section is also provided with a track relay designated by the reference character R with an exponent corresponding to the location and connected across the rails at the entrance end of the section. Thus, it will be seen that each track section is provided with a track circuit which comprises a transformer secondary 4, the rails 2 and 2^a of the section 45 in series and a track relay R.

Each section is also provided with a signal designated by the reference character S with an exponent corresponding to the location, this signal having a semaphore capable of 50 assuming three positions at 0, 45 and 90 angular degrees with respect to its mast in which positions the signal indicates "proceed", "caution" and "stop", respectively. The means for controlling these signals form 55 no part of my present invention and so are omitted from the drawing. It is sufficient to say that each signal indicates stop when the corresponding section is occupied, caution when the corresponding section is unoccupied, and proceed when the corresponding section and the section next in advance are both unoccupied.

Associated with each signal is a pole 60 changer designated by the reference character P with an exponent corresponding to the location, which pole changer is operated by the semaphore and assumes one position 65 when the semaphore is at proceed or caution, and another position when the semaphore is at stop. Each signal also operates a circuit controller designated by the reference character D with an exponent corresponding to the location. This circuit controller is open 70 when the semaphore is at stop, closed to one circuit when the semaphore is at caution and closed to another circuit when the semaphore 75 is at proceed.

The polarity of the relative instantaneous 80 current in each track circuit is controlled by the pole changer P for the signal immediately in advance. Referring for example, to transformer T^a, when the associated signal S^a is at proceed or caution, the left 85 hand terminal of the primary 3 of the transformer T^a is connected through wire 6, pole changer P^a, wires 8 and 9 to the upper 90

of the line wires 11 and thence to the generator 12, while at the same time, the right hand terminal of the primary 3 is connected by wire 7, pole changer P^A and wire 10 to the other of the line wires 11^a. The section to the left of the point A is then supplied with track circuit current of what I shall term "normal" relative instantaneous polarity. When the signal S^A is at stop, the pole changer P^A assumes the position shown in the drawing at P^C and the wire 6 is now connected to wire 10 while wire 7 is now connected to wire 9, thus the relative instantaneous polarity of the transformer is reversed and the section to the left of A is now supplied with track circuit current of what I shall term "reverse" relative instantaneous polarity.

Each section is provided with an impedance 13 connected across the rails adjacent to the entrance end of the section, a similar impedance 16 connected across the rails adjacent the exit end of the section, and two more similar impedances 14 and 15 connected across the rails at an intermediate point. Each section is also provided with a device for alternately making and breaking a circuit, which device is designated by the reference character E with an exponent corresponding to the location, and which device as shown in Fig. 1 is a slow acting relay having a magnet coil connected in series with its own back contact.

Each section is also provided with means for supplying a current, which I shall hereinafter call a "local" current, to the rails of the section in parallel. As here shown the immediate source of local current for each section is a line transformer designated by the reference character G with an exponent corresponding to the location. Each of these transformers comprises a primary winding 17 constantly supplied with current from the line wires 11 and 11^a, and two secondary windings 18 and 19. Referring particularly to transformer G^B , the secondary winding 19 has a circuit over which local current flows from its left hand terminal through wire 20 to the mid-point of the impedance 13 of section B-C, through both rails of section B-C in parallel, through the halves of the impedance 14, and wire 21 back to the right hand terminal of the secondary 19 on transformer G^B . The other secondary 18 of transformer G^B has a circuit which passes from its left hand terminal through wire 36 to the mid-point of the impedance 15, through both rails of the section A-B in parallel, through the impedance 16, wires 34 and 33, back contact 31-32 of the slow acting relay E^B , wire 30, energizing winding of the relay E^B , wire 29, contact 26-27 of circuit controller D^B , wire 25, front contact 23-24 of track relay R^B , and wire 22 back to the right hand terminal of the winding 18 on transformer G^B . This circuit is closed only

when relay R^B is energized, relay E^B is de-energized, and signal S^B is at the caution position under which conditions relay E^B alternately opens and closes its back contact, as explained in detail hereinafter, and local current is then intermittently supplied to the rails of section A-B between impedances 15 and 16. This circuit is provided with a branch which passes from wire 34, through wire 35, contact 26-28 on circuit controller D^B , back to wire 25, thus omitting relay E^B . This branch is closed only when signal S^B is in the proceed position. The local current then supplied to the track rails of section A-B is uninterrupted.

One form of train carried apparatus designed to cooperate with the trackway circuits and apparatus shown in Fig. 1 is shown in Fig. 6. This equipment comprises two inverted U-shaped magnetizable cores 22^T mounted in front of the first axle Z on the locomotive and arranged transversely above the two track rails 2 and 2^a, respectively, each of these cores being provided with a winding designated F^T . Located at some other point on the train, such as in the rear of the first axle, is another pair of magnetizable cores 22^L, located above the track rails 2 and 2^a, respectively, and disposed transversely with respect thereto, each of these cores carrying a winding designated F^L . The windings F^T are so connected that the voltages induced therein due to current flowing in opposite directions in the two rails at any given instant are additive, and so it will be seen that track circuit current in the rails will induce current in the circuit including the windings F^T . These two windings I will hereinafter refer to collectively as the "track coil". The two windings F^L are so connected that the voltages induced therein by currents flowing in the same direction in the two rails at a given instant are additive and so it will be seen that local current in the track rails will induce current in the circuit including the winding F^L . These two windings I will hereinafter refer to collectively as the "local coil". The terminals a and b of the track coil F^T are connected through suitable amplifying means K, to the winding 37 on a three-position two element relay N. The terminals a and b of the local coil F^L are connected, through suitable amplifying means L, to the other winding 38 on the relay N. This relay also has three movable contact fingers 39, 40 and 41. When the rails 2 and 2^a are supplied with local current and track circuit current of normal relative polarity the relay N is energized so that the fingers 39, 40 and 41 are swung to the left thus closing the contacts 39-42 and 41-46 which I will call normal contacts. When the rails 2 and 2^a are supplied with local current and track circuit current,

the relative polarity of either of which currents is reversed, the relay N is energized so that the fingers 39, 40 and 41 are swung to the right closing the contacts 39—43 and 41—45 which I will therefore call reverse contacts. When either the local or the track current is interrupted, the relay N becomes de-energized and the fingers 39, 40 and 41 swing to their intermediate positions closing the contact 40—44 which I will call a back contact. It will therefore be clear that the direction of energization of relay N depends upon the relative polarity of the track circuit and local currents rather than upon the absolute polarity of either of these currents at any instant. Two magnets H and M are also provided on each locomotive and are so arranged in combination with certain governing apparatus not shown in the drawing that when the magnet H is energized and the magnet M is de-energized, the governing apparatus permits the train to proceed at high speed such as 65 miles per hour. When the magnet H is de-energized, and the magnet M is energized, the governing apparatus prevents the train from exceeding an intermediate speed of 35 miles per hour. When magnets H and M are both de-energized the governing apparatus prevents the train from proceeding at speeds in excess of a low value, such as 10 miles per hour. The high speed magnet H is provided with a circuit which passes from the left hand terminal of a source of energy such as a battery O through wires 47 and 48, normal contact 41—46 on relay N, wire 49, winding of magnet H, and wires 50, 51 and 52, back to the right hand terminal of the battery O. This circuit is closed only when the relay N is energized in the normal direction. The magnet M is provided with a circuit which passes from the left hand terminal of the battery O, through wires 47 and 48, reverse contact 41—45 of relay N, wire 54, winding of the magnet M, and wires 53 and 52, back to the right hand terminal of the battery O. This circuit is closed only when the relay N is energized in the reverse direction.

The locomotive is also provided with a slow-acting relay J and an indicating device as a lamp 200. The lamp 200 is provided with a circuit which passes from the left hand terminal of the battery O, through wires 47, 55, 56 and 61, normal contact 39—42 of relay N, wire 63, front contact 63^a of relay J, wire 60, lamp 200, and wires 64, 51 and 52 back to the right hand terminal of battery O. This circuit is provided with a branch running from wire 56, through wire 62, reverse contact 39—43 on relay N and back to wire 63. It follows that the circuit for the lamp is closed when the relay N is energized in either the normal or reverse direction and the relay J is also energized. This relay J is provided with a circuit which passes from the left hand terminal of battery O, through wires 47, 55 and 57, back contact 40—44 on relay N, wire 58, winding of relay J, and wires 59, 64, 51 and 52, back to the right hand terminal of the battery O. This circuit is closed only when the relay N is de-energized.

The operation of the entire apparatus is as follows:

As shown in Fig. 1, a train V occupies the section to the right of C so that signal S^c is at stop and signal S^b is at caution. Track circuit current of reverse relative polarity is supplied to the rails of the section B—C, and local current is supplied to the rails of section B—C between the impedances 13 and 14 by transformer G^b but no local current is supplied to the rails of section B—C between the impedances 15 and 16. The rails of the section A—B are supplied with track circuit current of normal relative polarity by transformer T^b and with local current between impedances 13 and 14 by transformer G^a. Since the signal S^b is at caution, local current is supplied to section A—B from 15 to 16 through slow-acting relay E^b. As soon as this circuit is closed, however, relay E^b opens its back contact 31—32, thus interrupting the flow of local current between the impedances 15 and 16. This also opens the circuit to the coil of the relay which becomes de-energized and after a definite time interval closes its back contact, thus repeating the cycle and alternately closing and opening the circuit for the local current in section A—B between impedances 15 and 16. Inasmuch as signal S^a is at proceed position, the section to the left of A is supplied with local current and with track current of normal relative polarity. Now if a train moves along this track in the direction of the arrow, it may proceed at high speed as far as point B. As the train passes impedances 14 and 15 in section A—B, however, the light 200 in the locomotive cab begins to flash. This is accomplished in the following manner: When the train enters that portion of the track to which the local current is intermittently supplied, the relay N is alternately energized in the normal direction and de-energized. The governing mechanism controlled by magnets H and M require a definite time interval to operate and this mechanism is so designed that the time intervals between successive de-energizations of relay N is less than the time required for the governing mechanism to act and hence this equipment does not have time to reduce the speed of the train following one deenergization, before the relay is again energized, thus restoring the circuit to its normal condition. But when the relay N is de-energized, the slow release relay J is energized. When

next in sequence the relay N is energized and its normal contact closed, the lamp will flash momentarily, since the slow release relay J will be retarded in opening its contact till after the relay N has closed again. Before the slow-acting relay J can again open its front contact the back contact of the relay N is again closed and the relay J is again energized. Thus the front contact of the relay J will remain closed and the lamp 200 will flash each time the relay N is energized. The relative lengths of time of this cycle may be regulated by variation in the time elements of the various elements of the circuits. When the lamp 200 flashes the engineman knows that he is approaching a caution signal and may conduct himself accordingly. As the train passes the point B, the reversed relative polarity of the track circuit current causes the relay N to be energized in the reverse direction and this de-energizes magnet H and energizes magnet M, thus imposing on the train a speed limit of 35 miles per hour. As the train passes the impedances 14 and 15, the interruption of the local current de-energizes the magnet M and the train is prevented from proceeding at a speed in excess of 10 miles per hour.

In the modified form of train carried apparatus shown in Fig. 7 I have omitted the magnets H and M with their controlling contacts for the sake of simplicity. Also I have omitted, for the same reason, the circuits for the control of windings 37 and 38 of relay N. The circuit for the first slow acting relay J is the same as in Fig. 6, but a second slow acting relay U has been added, and this relay is inserted in the circuit in place of the lamp 200 in Fig. 6. The circuit for lamp 200 is now from the left hand terminal of the battery O through wires 47 and 65, front contact 66-67 of relay J, wire 68, front contact 68^a of relay U, wire 60, lamp 200 and wire 52 back to right hand terminal of battery O. This circuit is closed only when relays J and U are both energized. The operation of this apparatus in the zone where local current is intermittently supplied to the rails is as follows: When the local current is interrupted the first time the relay N is de-energized and so closes its back contact 40-44. This closes the circuit for the slow-acting relay J which becomes energized and subsequently remains closed during the intermittent operation of relay N. When relay N is energized again it will close the circuit for the slow-acting relay U, which latter will subsequently remain closed because of its slow-release characteristic. As soon as relay U closes, the lamp 200 will be lighted and will continue to burn steadily until the intermittent operation of relay N ceases.

In Fig. 8 I have shown the same apparatus as in Fig. 7 except that the circuit for

the lamp 200 passes from wire 47 through wire 57, back contact 40-44 of relay N, and thence as before to battery O, thus including back contact 40-44 in its circuit. The operation is exactly as in Fig. 7 except that the lamp 200 now lights only when relay N is de-energized thus giving a flashing indication, instead of a steady indication as was the case in Fig. 7.

In Fig. 2, the apparatus is the same as that shown in Fig. 1 except that each track relay R is in this case a three-position two-element relay having one winding 70 constantly supplied with alternating current from the secondary winding 71 of the associated transformer G. The other winding 72 of the relay R is connected across the rails at the entrance end of the section. The track circuit current is, under these conditions, supplied from a winding 4 on the transformer G and the relative polarity of the current is controlled by the contact fingers 73 and 74 on the relay R. Referring particularly to transformer G^A, the associated relay R^A, as shown in the drawing, is energized in the normal direction. In this position the left hand terminal of secondary winding 4 is connected to rail 2^a through wire 83, normal contact 73-75 of relay R^A and wire 81 and the right hand terminal of winding 4 is connected to rail 2 through normal contact 74-78 of relay R and wire 82. When relay R^A is energized in the reverse direction the left hand terminal is connected to rail 2^a through wire 84, reverse contact 73-77 of relay R^A and wire 81 and the right hand terminal of this winding is connected to rail 2 through wire 86, reverse contact 74-80 and wire 82. It is clear, therefore, that track circuit current of the same relative polarity which I shall term "normal" relative polarity is supplied to the rails of the section to the left of point A when relay R^A is energized in either reverse or normal direction. When the relay R^A is de-energized the left hand terminal of secondary winding 4 is connected to rail 2 through wire 87, back contact 74-79 of relay R^A, and wire 82 and the right hand terminal of this winding is connected to the rail 2^a through wire 150, back contact 73-76 of relay R^A, and wire 81. In this case track circuit current of the other relative polarity which I shall term "reverse" relative polarity is supplied to the rails of the section to the left of A. The winding 18 of each transformer G, which winding supplies local current to the rails of the adjacent section between the impedances 15 and 16, is controlled by means of the contact finger 88 on the associated relay R. Referring particularly to transformer G^B, the winding 18 has a circuit which passes from its left hand terminal through wire 89 to the mid-point of the impedance 15, through both rails of the

section in parallel to the impedance 16, wire 94, reverse contact 88-91 of relay R^B , wire 92, winding of slow-acting relay E^B , wire 97, back contact 31-32 of relay E^B , wires 96 and 95, back to the right hand terminal of winding 18 on transformer G^B . This circuit is closed only when the relay R^B is energized in the reverse direction and relay E^B is de-energized, but as soon as current starts to flow through this circuit the relay E^B is picked up, breaking the circuit through its back contact. This relay then becomes de-energized and the cycle is repeated with the result that the portion of section A-B between impedances 15 and 16 is supplied with an intermittent flow of alternating current as long as the relay R^B is energized in the reverse direction, thus actuating the train carried apparatus of Figs. 6, 7 or 8 exactly as in Fig. 1. The circuit for the winding 18 is provided with a branch which passes from wire 94 through normal contact 88-90 of relay R^B and wire 93 back to wire 95, thus omitting the slow-acting relay E^B . This circuit is closed only when the relay R^B is energized in the normal direction in which case local alternating current is constantly supplied to the rails of the section A-B between the impedances 15 and 16 by the winding 18 of transformer G^B . Thus it is seen that exactly the same conditions of local and track circuit current exist in this case for a given condition of traffic in advance as for Fig. 1.

Another arrangement of trackway circuits embodying my invention and arranged to co-operate with the train-carried apparatus shown in Figs. 6, 7 and 8 is shown in Fig. 3. In this case I obtain the same results as in Figs. 1 and 2 but I reverse the local current instead of the track circuit current to produce the intermediate speed condition. Each track section is provided with a transformer designated by the reference character X with an exponent corresponding to the location, and a thermostat designated by the reference character Y with an exponent corresponding to the location. Each transformer X is provided with three windings 125, 126 and 127, and each thermostat is provided with a heating coil 120 and a movable finger 121 which normally closes the contact 121-122. When the heating element 120 is energized, the finger 121 is moved to the left and closes the contact 121-123. Referring particularly to section A-B the circuits for the local current are as follows: from the left hand terminal of the winding 18 of transformer G^B , through wires 101 and 112 to the mid-point of the impedance 16, through both the rails of section A-B in parallel, through impedance 13, wire 130, winding 126 of transformer X^A , wire 113, front contact 23-24 of relay R^B and wire 116 back to the right hand terminal of the winding 18 of transformer G^B . This circuit is closed only when relay R^B is energized, under which condition local current of normal relative polarity is supplied to the rails of section A-B throughout their length. A branch is provided for this circuit which passes from wire 101 through wire 118, contact 121-123 of thermostat Y^B , wires 131 and 117, to rails of section A-B through impedance 15. The circuit is closed through this branch only when thermostat Y^B is energized, under which condition local current is shunted away from that portion of section A-B between impedances 15 and 16. The winding 19 of transformer G^B is provided with a circuit which passes from its left hand terminal through wire 132, back contact 23-114 of relay R^B , wire 113, transformer winding 126, impedance 13, then through the rails of section A-B in parallel, impedance 15, wire 117, and wire 109 back to the right hand terminal of the secondary 19 of transformer G^B . This circuit is closed only when relay R^B is de-energized and section A-B is then supplied with local current of reverse relative polarity between impedances 13 and 15. The heating element 120 of thermostat Y^B is provided with a circuit which passes from the upper terminal of winding 125 on transformer X^B , through wire 119, contact 121-122 of thermostat Y^B , winding 120 of thermostat Y^B , and wire 124 back to the lower terminal of winding 125 on transformer X^B . This circuit is closed only when the contact 121-122 of thermostat Y^B is closed. The transformer X^B is provided with a winding 127 constantly supplied with alternating current from generator 12 through line wires 11, 11^a, and wires 128 and 129. Each transformer X is so constructed and connected that when the local current supplied to winding 126 thereof is of normal relative polarity with respect to the track circuit current, the voltages induced in winding 125 by the currents in windings 126 and 127 oppose each other at any instant and consequently no current flows in winding 125. Should the relative polarity of the current in winding 126 be reversed the voltages induced in winding 125 would be additive and an alternating difference of potential would be created between the terminals of winding 125.

The operation of this apparatus is as follows: As shown in Fig. 3, a train V occupies the section to the right of C. The relay R^C is de-energized thus closing the circuit for winding 19 of transformer G^C which supplies local current of "reverse" relative polarity to the rails of section B-C between the impedances 13 and 15 while no local current is supplied to the rails of this section from impedance 15 to impedance 16. The relay R^B is energized, thus supplying local current of normal relative polarity to the

rails of section A—B between impedances 13 and 16. In transformer X^B the voltages induced in winding 125 by currents in windings 126 and 127 are additive and the winding 125 is energized, thus heating the thermostat Y^B which closes the contact 121—123 and short circuits the rails of the section A—B between impedances 15 and 16, thus reducing the local current through that portion of the section to such value that the train carried relay N will be de-energized. But the opening of contact 121—122 on the thermostat will de-energize its heating coil which will allow contact 121—122 to close again thus repeating the cycle as long as current of reverse relative polarity is supplied to the winding 126 of transformer X^B. The relay R^A is energized, thus supplying local current of normal relative polarity to the rails of the section to the left of A throughout its entire length. It will be noted that the voltages induced in winding 125 of transformer X^A by the currents in winding 126 and 127 now are opposite in direction and being equal and opposite the result is zero induced voltage in winding 125 and hence the thermostat Y^A is not energized. It is evident that the intermittent supply of alternating current to the rails of a portion of the section in rear of a caution signal as at S^B is accomplished as in Figs. 1 and 2 but by different means.

Fig. 4 shows another arrangement for accomplishing the same result as the apparatus shown in Figs. 1, 2 and 3, and is exactly the same as that shown in Fig. 3 except that each thermostat Y is provided with a second contact finger 121^a mechanically operated by finger 121 but electrically insulated therefrom. Finger 121^a connects the left hand terminal of secondary 18 on transformer G to either impedance 15 or impedance 16 of the section in rear of the thermostat, thus alternately supplying alternating local current to the rails of the section between the entrance and the exit end and between the entrance end and an intermediate point in the section. The contact 121 still makes and breaks the heating circuit of the thermostat as before and the operation of this system is precisely the same as of that shown in Fig. 3.

In Fig. 5 a polarized relay W is substituted for the thermostat Y. This relay is provided with two windings 132 and 99 and is responsive to the relative polarity of the currents supplied to these windings. Referring particularly to relay W^A, the winding 99 is energized from the secondary 98 of the transformer X^A. The other winding 132 is provided with a circuit which passes from line wire 11 through wire 133, winding 132 of relay W^A, wire 134, an element 100 having a high positive temperature coefficient, and wires 136 and 135 to line wire 11^a. This

circuit is provided with a branch which passes from the wire 134 through wire 140, normal contact 103—107 of relay W^A and wire 141 back to wire 136. This branch is closed only when relay W^A is energized in the normal direction. A second branch is provided for this circuit which branch passes from wire 134 through wire 140, back contact 103—142 of relay W^A and wire 139, an element 138 having a high negative temperature coefficient, back to wire 135. This branch is closed only when relay W^A is de-energized. The primary winding 126 is supplied with current of the one or the other relative polarity according as the local current supplied to the section A—B is of normal or reverse relative polarity. Since the current supplied to winding 132 of relay W^A is always of the same instantaneous relative polarity, it follows that the relay will be energized in the normal or the reverse direction depending upon the instantaneous relative polarity of the local current supplied to section A—B.

As shown in the drawing, the section to the right of C is occupied by a vehicle V. This interrupts, as before, the track circuit current in this section and causes relay R^C to be de-energized. Thus local current of reverse relative polarity is supplied to the rails of section B—C between impedances 13 and 15 but no local current is supplied to the rails of this section between impedances 15 and 16. The section to the left of A is supplied with local current of normal relative polarity throughout its length. The reversal of local current in section B—C causes relay W^B to be energized in the reverse direction so that the current in winding 132 of relay W^B is forced to flow through the unit 100. The current raises the temperature of this unit and due to its high positive temperature coefficient, the resistance of this unit is increased thus decreasing the current through the winding 132 which allows relay W^B to open, closing its back contacts. This disconnects the left hand side of transformer secondary 18 from impedance 16 of section A—B and connects it to impedance 15 through back contact 102—105. The branch through back contact 103—142 and unit 138 is also closed. As this unit heats up from the current passing through it, the resistance decreases and when the current has reached the required value the relay W^B is picked up in the reverse direction and the element 100, having cooled off, repeats the cycle. Thus the current between impedances 15 and 16 of a section is alternately supplied and interrupted in rear of a caution signal and co-operates with the train carried equipment as explained hereinbefore.

Although I have herein shown and described only a few forms and arrangements of railway traffic controlling apparatus em-

bodging my invention, it is understood that various changes and modifications may be made therein within the scope of the appended claims, without departing from the 5 spirit and scope of my invention.

Having thus described my invention, what I claim is:

1. Railway traffic controlling apparatus comprising track rails, means for applying 10 an alternating difference of potential across said rails and another alternating difference of potential along said rails, means for at times intermittently interrupting the supply of one of said potential differences to the 15 rails, train carried governing means controlled jointly by the currents in the track rails due to said potential differences but not affected by said intermittent interruption of the one difference of potential, and other 20 train carried governing means responsive to said intermittent interruption of said one difference of potential.

2. Railway traffic controlling apparatus comprising track rails, means for applying 25 an alternating difference of potential across said rails and another alternating difference of potential along said rails, means for at times intermittently interrupting the supply of one of said potential differences to the 30 rails, train carried governing means controlled jointly by the currents in the track rails due to said potential differences but not affected by said intermittent interruption of the one difference of potential, and a 35 train carried signal responsive to said intermittent interruption of said one difference of potential.

3. Railway traffic controlling apparatus comprising track rails, means for applying 40 an alternating difference of potential across said rails and another alternating difference of potential along said rails, means for at times intermittently interrupting the supply of the second of said differences of potential, 45 train carried governing means controlled jointly by the currents in the track rails due to said potential differences but not affected by said intermittent interruption of the one difference of potential, and other train carried governing means responsive to said one 50 difference of potential.

4. Railway traffic controlling apparatus comprising track rails, means for applying an alternating difference of potential across 55 said rails and another alternating difference of potential along said rails, means for at times intermittently interrupting the supply of the second of said differences of potential, train carried governing means controlled jointly by the currents in said track rails due to said potential differences but not affected by said intermittent interruption of the second difference of potential, and a train carried signal responsive to the

intermittent interruption of the second difference of potential. 65

5. In combination, a section of railway track, means for supplying alternating current to the rails of said section in series, means for supplying a second alternating current of one relative polarity or the other to the rails of said section in parallel between the entrance end and an intermediate point in the section, means for supplying a third alternating current to the rails of said section in multiple between said intermediate point and the exit end of the section, means for periodically interrupting said third current, and a train carried indicator controlled by said currents. 70 75 80

6. In combination, a section of railway track, means for supplying an alternating current of one relative polarity or the other to the rails of said section in series, means for supplying a second alternating current to the rails of said section in parallel between the entrance end and an intermediate point in the section, means for supplying a third alternating current to the rails of said section in multiple between said intermediate point and the exit end of the section, means for periodically interrupting said third current, and a train carried indicator controlled by said currents. 85 90 95

7. In combination, a section of railway track, a trackway circuit comprising the two rails of said section in series, a second trackway circuit comprising the two rails of said section in multiple between the entrance end and an intermediate point in the section, a third trackway circuit comprising the two rails of said section in multiple between the exit end and an intermediate point in the section, means for supplying alternating currents to the said circuits, means for reversing the relative polarity of the current in one of the first two said circuits, means controlled by traffic conditions in advance for periodically interrupting the current in the said third circuit, and a train carried indicator responsive to said periodic interruption but not responsive to steady condition of the current in said third circuit. 100 105 110

8. In combination, a section of railway track, a trackway circuit comprising the two rails of the section in parallel between the exit end and an intermediate point in the section, means controlled by traffic conditions in advance for intermittently supplying alternating current to said circuit, and a train carried indicator controlled in part by said current. 115 120

9. In combination, a section of railway track, a trackway circuit comprising the two rails of the section in parallel between the exit end and an intermediate point in the section, a trackway signal controlled by traffic conditions in advance, means con- 125

trolled by said signal for intermittently supplying alternating current to said circuit, and a train carried indicator controlled in part by said current.

5 10. In combination, a section of railway track, a trackway circuit comprising the two rails of the section in parallel between the exit end and an intermediate point in the section, a trackway signal controlled by traffic conditions in advance, a slow-acting relay, means controlled by said signal and said relay for intermittently supplying alternating current to said circuit, and a train carried indicator controlled in part by said current.

15 11. In combination, a first, a second and a third section of railway track, a track relay for the third section, a track relay for the second section, a trackway circuit comprising the two rails of the first section in parallel between the exit end and an intermediate point in the section, means controlled by said relay for intermittently supplying said circuit with alternating current, and a train carried indicator controlled in part by said current.

20 12. In combination, a section of railway track, a train carried relay having two windings, means controlled by alternating current flowing in the same direction in the two rails of said section for energizing one winding of said relay, means controlled by alternating current flowing in opposite directions in the two rails of said section for energizing 25 the other winding of said relay, means for supplying a periodically interrupted alternating local current to the rails of the section in parallel, a train carried indicator, and means controlled by said relay for alternately energizing and de-energizing said indicator when said relay is alternately energized and de-energized.

30 13. In combination, a section of railway track, a train carried relay having two windings, means controlled by alternating current flowing in the same direction in the two rails of said section for energizing one winding of said relay, means controlled by alternating current flowing in opposite directions in the two rails of said section for energizing the other winding of said relay, a slow-acting relay provided with a circuit including a source of energy and a back contact on said first relay; and an indicator provided with a circuit including a source of energy, a front contact on said slow-acting relay, and either a normal or a reverse contact on said first relay.

35 14. In combination, a railway track, means for at times continuously supplying said track with energy and for at other times periodically interrupting the supply of such energy, and train carried governing apparatus responding selectively to such continuous

40 and periodically interrupted supply of energy.

45 15. In combination, a railway track, means for at times continuously supplying said track with energy and for at other times periodically interrupting the supply of such energy, a main train carried relay responding to both the continuously supplied and the periodically interrupted supply of energy, a slow releasing relay on the train energized each time said main relay becomes de-energized and designed to remain continuously energized during operation of the main relay in response to periodic interruption of the trackway energy, and a signal controlled jointly by said main and slow releasing relays.

50 16. In combination, a railway track, means for at times continuously supplying said track with energy and for at other times periodically interrupting the supply of such energy, a main train carried relay responding to both the continuous and the periodically interrupted supply of energy in the trackway, a slow releasing relay on the train continuously energized when said main relay is operating in response to periodically interrupted trackway energy, and a signal controlled jointly by said main and slow releasing relays.

55 17. In combination, a railway track, means for at times continuously supplying said track with energy and for at other times periodically interrupting the supply of such energy, and traffic governing apparatus responding selectively to such continuous and periodically interrupted supply of energy.

60 18. In combination, a railway track, means for at times continuously supplying said track with energy and for at other times periodically interrupting the supply of such energy, a main train carried relay arranged to be continuously energized during the continuous supply of energy to the track and to open periodically during periodic interruption of such energy supply, a slow releasing relay on the train controlled by said main relay and arranged to be continuously closed during operation of the main relay in response to periodic interruption of the energy supply, and signaling means on the train controlled by said main and slow releasing relays.

65 19. In combination, a railway track, means for supplying said track with periodically interrupted energy, and train carried apparatus selectively responsive to such periodically interrupted energy but not to energy continuously supplied.

70 20. In combination, a railway track, means for supplying said track with periodically interrupted energy, a main train carried relay arranged to open periodically in response to periodic interruption of such en-

ergy supply, a slow releasing relay on the train controlled by said main relay and arranged to be continuously closed during operation of the main relay in response to periodic interruption of the energy supply, and signaling means on the train controlled by said main and slow releasing relays.

21. In combination, a railway track, means for at times continuously supplying said track with energy and for at other times periodically interrupting the supply of such energy, a main relay arranged to be continuously energized during the continuous supply of energy to the track and to open periodically during periodic interruption of such energy supply, a slow releasing relay controlled by said main relay and arranged to be continuously closed during operation

of said main relay in response to periodic interruption of the energy supply, and traffic governing apparatus controlled by said main and slow releasing relays. 20

22. In combination, a railway track, means for supplying said track with periodically interrupted energy, a main relay arranged to open periodically in response to periodic interruption of such energy supply, a slow releasing relay controlled by said main relay and arranged to be continuously closed during operation of said main relay in response 25 to periodic interruption of the energy supply, and traffic governing apparatus controlled by said main and slow releasing relays. 30

In testimony whereof I affix my signature.
HERBERT A. WALLACE.
